UNITED STATES PATENT OFFICE.

SEBASTIAN F. DIETRICH, OF CUDAHY, WISCONSIN, ASSIGNOR TO NON-BREAKABLE BUTTON CORPORATION, OF MILWAUKEE, WISCONSIN, A CORPORATION OF WISCONSIN.

PUNCH PRESS.

Application filed August 7, 1922. Serial No. 580,201.

To all whom it may concern:

Be it known that I, SEBASTIAN F. DIETRICH, a citizen of the United States, and resident of Cudahy, in the county of Milwaukee and 5 State of Wisconsin, have invented certain new and useful Improvements in Punch Presses; and I do hereby declare that the following is a full, clear, and exact description thereof.

10 The invention relates to punch presses for punching rubber wads from a blank of stock and depositing them on a mould to be formed into buttons.

It comprises a die-plate having openings 15 therein and punches for acting upon stock and pressing it through the openings, forming it into wads and depositing the wads on tins which are carried by a mould.

The object of the invention is to substantially simultaneously 20 punch wads of plastic rubber from a blank and deposit them on a mould, whence they may be formed into buttons. This operation is designed to effectuate economy of time, labor and material. 25 Whereas heretofore the practice of depositing the wads on to the mould by hand has been attended with considerable delay and inconvenience, the operation necessitating several distinct movements of the hand for 30 the fixing of a single wad in position, the invention accomplishes the cutting out of a large number of wads and their affixation to the mould in a moment's time, with a minimum of labor and with substantially no 35 wastage of material. Only one man is required to operate the machine. The stock may be inserted conveniently and quickly, after which the depression of a pedal by a foot causes the downward movement of the 40 punches, the complete process of forming and affixing the wads in position requiring but a moment for its completion. Consequently a great saving of time and labor 45 results.

Again, whereas heretofore it has been possible to mould a number of buttons from a blank of stock without necessitating formation of the individual wads and their 50 manual positioning in the mould, yet this operation has been expensive and wasteful, inasmuch as it resulted in wasting of the material between the buttons which became vulcanized simultaneously with the buttons, so that its plastic character was destroyed 55 and its value greatly lowered, inasmuch as

after having been vulcanized it could not then be worked up with the stock and formed into buttons.

With the above and other objects in view, 60 which will appear as the description proceeds, my invention resides in the novel construction, combination and arrangement of parts, substantially as hereinafter described and more particularly defined by the appended claims, it being understood that such 65 changes in the precise embodiment of the herein disclosed invention may be made as come within the scope of the claims.

In the accompanying drawing, I have 70 illustrated one complete example of the physical embodiment of the present invention constructed according to the best mode I have so far devised for the practical application of the principles thereof, and in 75 which:

Figure 1 is a rear elevation of the device showing the upper part of the legs broken away.

Figure 2 is a side elevation of the machine.

Figures 3, 4, 5, and 6 are side elevations 80 of the die punches and associated parts, bringing out the several steps in the process.

Figure 7 is a detail, showing the punch and its manner of cooperation with the die-plate.

Figure 8 is a plan of a wad or disc resulting from the punching operation.

Forelegs 10 are provided formed of angle iron. They are strengthened by braces 11 running from front to rear. A brace 12 is 90 provided across the front and a brace 13 in the rear. From the latter a support 14 extends rearwardly, as does also a support 15 secured to a rear leg. On these supports bearings 16 are located, rotatably supporting a shaft 17 providing a pivot for a lever 18 which is rigid with a fork 19 for controlling the clutch 20 on shaft 21 operated by the motor 22.

Spring 23 is secured at one end to brace 12 100 and at the other to lever 18, and operates to maintain the lever normally in position, rendering the clutch inoperative. The clutch controls the rotation of shaft 24 journalled in bearings 25 and carried on a plate 26 extending from front to rear and secured to braces 12 and 13. Worm 27 rigid with shaft 24 is operative to rotate worm gear 28 on shaft 29 journalled in bearings 30 supported by braces 11. Shaft 29 extends laterally be- 110

yond the bearings and operates through gears 31—31' to actuate gears 32—32' on shaft 33 journaled in a bottom plate 34 for the press.

5 The bottom plate is secured to legs 10 by bolts 35. It is provided with a plurality of vertical cylindrical openings in which guide posts 36 are positioned, the guide posts being enlarged intermediately to form shoulders 10 37 resting on mould guides 38 secured to the bottom plate 34. The guide posts are fixed in position by nuts 39 threaded on their lower ends. Each of the guide posts 36 is bored longitudinally to receive a trip rod 40 15 which is adjustably secured to a rectangular frame 41 by means of nuts 42.

To the side members of the frame a pair of links 43 are pivotally secured by bolts 44, the upper ends of the links being pivoted to arms 45 rigid with a shaft 46 rotatable in a bearing 47. The shaft carries an arm 48 having a roller 49 at its end adapted to contact with shaft 33 and a cam 50 rigid with the shaft 33.

25 Bottom plate 34 has a central opening to permit reception of the cam and arm 48. The cam terminates in rounded shoulders 51 disposed substantially one hundred and eighty degrees apart. A heavy top plate 52, 30 somewhat similar to bottom plate 34, is provided having a plurality of vertical openings slidably receiving bushings 53 having closed upper ends 54 against which springs 55, received in recesses in the ends of guide posts 36, are adapted to contact. Trip rods 40 are provided with nuts 56 at their upper ends adapted to contact with the ends of the bushings. A shaft 57 extends transversely of the top plate journaled in bearings 58 40 on the sides.

A pair of links 59 extend from shaft 57 to shaft 33. Eccentrics 60 are provided in the upper ends of links 59 and envelop shaft 57. By means of nuts 61 integral therewith, 45 the eccentrics may be adjusted to vary the distance between shafts 33 and 57. The eccentrics are slotted, as shown, at 62 and are prevented from outward movement on shaft 57 by cotters 63. The ends of shaft 33 are 50 keyed to eccentrics 64, rotatable in the lower ends of links 59. It is apparent that the rotation of shaft 33 operates through links 59 to raise and lower top plate 52.

To the top plate punch plate 65 is secured by dowels, or other suitable means. The punch plate has a number of openings therein, and adjacent the upper part of the openings is countersunk so that punches 66 may be riveted in place. Disposed beneath the punch plate is a stripper plate 67 maintained in fixed relation to die-plate 68 by means of lateral spacers 69. The stripper spacers and die-plate are secured rigidly together and the stripper and die-plate are provided with a number of alined

holes adapted to receive the punches 66. They are provided also with openings receiving bushings 53, the openings in the spacers 69 being enlarged to receive a collar 70 rigid with the bushing.

In one phase of operation of the machine a mould 71 is positioned upon the bottom plate, its rearward limit of movement being determined by projections 72 on guides 38. The guides operate to center the mould 71 75 so that pairs of pins 73 thereon may be disposed immediately beneath the punches 66.

A mould having pairs of pins is provided when buttons having pairs of openings are to be made. Where a button with four 80 openings is to be made, pins are disposed in groups of four. The number of pins may be varied.

In operating the device, after the mould is put in place, which may be done when the parts are substantially in the positions shown in Figures 2 and 3, a rectangular blank of stock 74 is inserted between stripper plate 67 and die-plate 68. Lever 18 is then depressed, which operates, through the intermediate gearing to rotate shaft 33. As the center of eccentric 64 is at this time above the center of shaft 33, the movement causes links 59 to move downwardly, the eccentric traveling in a counter-clockwise direction looking at Figure 3. This brings the punches 66 in contact with the stock, as shown in Figure 4. The descent of the punches thus operates to punch out a number of wads 75 in the holes in die-plate 68, 90 and press these wads on to pins 73.

Figure 5 illustrates the relation of parts when the punches have completed the action of forming the wads from the stock. At this time roller 49 on arm 48 is positioned on the eccentric 50. The contact of the shoulder 51 with the roller operates through arm 48, shaft 46, arm 45 and frame 41, to elevate trip rods 40 so that nuts 56 are spaced above bushings 53.

When the punches 66 descend and perform the punching operation, the pressure produced thereby on the stripper plate 67 and die-plate 68 is such as to cause bushings 53 also to move downwardly. Consequently when trip rods 40 move upwardly, as described, springs 55, which have been compressed by the downward movement of the bushing, exert a lifting force and restore the stripper plate 67 to contact with punch plate 65, as shown in Figure 6. Nuts 56 are at this time spaced slightly above the upper ends of the bushings.

At this point of the operation the eccentric 64 is downwardly disposed with respect to the center of shaft 33. Further rotation of the shaft operates to lift links 59 and top plate 52, spacing punch plate 65 from stripper plate 67. The stripper plate is prevented from following punch plate 65.

to its uppermost position by contact of the upper ends 54 of the bushings with nuts 56 which operate to throw the entire weight of the trip rods 40 and frame 41 on the 5 bushings. The parts are then in the position shown in Figure 3. The operator may then remove his foot from the lever 18, causing the machine to come to rest. The mould may then be removed carrying therewith the 10 wads of rubber 75 supported on pins 73. The perforated blank of stock may also be removed and a new blank inserted, a new mould being substituted for the old.

One complete cycle of operation is thus accomplished. The blanks of stock are in a plastic condition and the wads positioned on the pins may be compressed between two parts of a mould, the pins serving to form the holes in the buttons. As is known to 15 those skilled in the art, the buttons are vulcanized in the mould. After the positioning of the blank of stock on the die-plate, the mere depression of lever 18 is operative to position the wads on the mould. 20 Thus a large number of wads may be put in place in but a moment of time.

This operation contrasts markedly with the methods heretofore employed, the positioning of the wads by hand being extremely slow, as several motions of the hand are necessary in the affixation of a single button, nor does the novel method result in a waste of the perforated blank of stock for the reason that this stock is not deposited upon the mould, but is removed 30 in its unvulcanized state. Thus the stock may be reused in forming other buttons.

I claim:—

1. The combination of a plurality of 40 punches adapted to operate upon stock, a mould, a plurality of pins on said mould, and means cooperating with said stock and said punches for forming wads from said stock, said punches being movable to deposit the 45 wads on said pins.

2. The combination of an upper plate having an opening therein, a lower plate having an opening therein aligned with said first mentioned opening, said plates being 50 adapted to receive stock therebetween, a mould, pins on said mould projecting into said second opening, a plunger, and means for moving said plunger through said openings for forming a wad from said stock and 55 depositing said wad on the pins.

3. The combination of a die-plate having an opening therein and adapted to receive a sheet of stock, a plunger for urging a wad from said stock through said opening, means 60 for causing relative motion between said plunger and die plate, a mould for receiving said wad, and means for separating said mould from said die-plate.

4. The combination of a stripper plate 65 having openings therein, a die-plate having

openings therein, said stripper plate and said die plate being adapted to receive stock therebetween, a mould provided with pins, a plurality of punches, means for moving said punches through said openings to force 70 wads of stock on to said pins, and means for moving said die-plate upwardly to release said pins and permit the withdrawal of said mould.

5. The combination of a stripper plate 75 having openings therein, a die-plate having openings therein aligned with the openings in said stripper plate, a mould, pins on said mould, a support for said mould, a plurality of plungers, means for moving said plungers through said aligned openings to force 80 wads on to said pins, and guiding means for centering said mould and said pins beneath said die-plate, whereby the pins will be positioned under the openings in said die-plate. 85

6. The combination of a bottom plate, a guide post secured thereto, a top plate, a bushing for said guide post in said top plate, said guide post having a longitudinal channel therein, and a trip rod slidable in 90 said channel.

7. The combination of a bottom plate, a post secured thereto, a top plate having an opening therein, a bushing for said guide post slidable in said opening, resilient means 95 tending to move said bushing upwardly with respect to said guide post, said guide post having a longitudinal opening therein, and a guide trip rod slidable in said opening.

8. The combination of a bottom plate having an opening therein, a guide post secured in said opening, said guide post having a longitudinal channel therethrough, a top plate having an opening therein, a bushing for said guide post slidable in said 105 opening, resilient means tending to move said bushing upwardly with respect to said guide post, a die plate trip rod slidable in said channel, and means for limiting the upward movement of said bushing with respect to said rod. 110

9. The combination of a bottom guide plate having a plurality of openings therein, a plurality of guide rods received in said openings having longitudinal channels therethrough, a trip rod slidable in said channels, a top plate having a plurality of openings therein, a plurality of bushings each slidable received in the openings in 115 said top plate, the upper ends of said bushings being closed, a plurality of trip rods each received in said channel, a spring interposed between the top of each of said bushings and each of said guide posts, a nut on the upper end of each of said guide posts contacting with the top of each of said bushings, a rotary shaft, a cam on said shaft, means cooperating with said cam for moving said die rods downwardly, an eccentric on said shaft, and means cooperating 120

125

130

with said eccentric and said top plate for lifting and lowering said top plate.

10. The combination of a bottom plate, a shaft rotatable thereon, a second shaft, 5 a cam on said first mentioned shaft, an eccentric on said first mentioned shaft, means on said second shaft adapted to cooperate with said first mentioned shaft and said cam for imparting rotary movement to said 10 second mentioned shaft, said second men-

tioned shaft being mounted to rotate on said bottom plate, a plurality of trip rods, and means cooperating with said second shaft to raise and lower said trip rods on the rotation of said second shaft. 15

In testimony that I claim the foregoing I have hereunto set my hand at Milwaukee, in the county of Milwaukee and State of Wisconsin.

SEBASTIAN F. DIETRICH.
